ATTORNEY

UNITED STATES PATENT OFFICE.

RUDOLPH LIEBMAN, OF ALLENtown, PENNSYLVANIA.

DESIGN FOR A PICTURE-FRAME.

SPECIFICATION forming part of Design No. 23,468, dated July 17, 1894.

Application filed June 19, 1894. Serial No. 515,070. Term of patent 3½ years.

To all whom it may concern:

Be it known that I, RUDOLPH LIEBMAN, a citizen of the United States of America, residing at Allentown, in the county of Lehigh and State of Pennsylvania, have invented and produced a new and original Design for Picture-Frames, of which the following is a specification, reference being had to the accompanying drawing, showing a face view thereof.

The design illustrated in said drawing consists essentially in the hop vine *a* bent to form a substantially rectangular sight or opening *b*. The lower ends or terminals of the

vine form the feet or rests *c c* of the frame. Part of the stems or twigs projecting from the vine bear hop leaves *d d*, and part bear hops *e*.

What I claim is—

The design for a picture frame, substantially as shown and described.

In testimony whereof I affix my signature in the presence of two witnesses.

RUDOLPH LIEBMAN.

Witnesses:

H. J. SHIPE,
MORRIS J. HEPLEN.
